SOENNECKEN, OF BONN-ON-THE-RHINE, GERMANY.

PAPER ROLL FOR ROLLER COPYING MACHINES.

1,415,084.

Specification of Letters Patent. Patented May 9, 1922.

Application filed October 24, 1913. Serial No. 797,097.

To all whom it may concern:

Be it known that I, Dr. RICHARD BERGER, engineer, a subject of the King of Bavaria, and residing at Bonn-on-the-Rhine, Venusbergweg, No. 23, in Germany, have invented 5 certain new and useful Improvements in Paper Rolls for Roller Copying Machines, (for which I have filed applications in Germany, March 14, 1913, No. S. 38520, VII, 10 55f; England, Oct. 9th, 1913, No. 22,824; France, Oct. 23rd, 1913, No. 62,541; Austria, Oct. 7th, 1913, no number.)

Roller copying machines require various auxiliary devices such as for instance a cutter for separating the copying paper into proper lengths, a feeder, for introducing the originals to be copied, a stamp marking the originals in a way showing that they were copied, and so forth.

It is desirable that these auxiliary devices work in co-action with each other, but, in such intervals as correspond to the lengths of the originals of different sizes, such for instance as a post-card, letter, and document 20 or foolscap size. In other words, the copying machine, should be arranged in such a manner that according to the size of originals to be copied, the auxiliary devices enter into co-action automatically in the proper intervals, thus feeding, cutting, and stamping, &c., at such a moment as corresponds to the size the machine is adjusted to.

Various means have been proposed to that end, such as intermediate exchangeable gearing and the like, invariably of a nature rendering the machine more complicated than necessary and more difficult of adjustment and control.

According to the present invention it is 40 the copying paper itself that is utilized for controlling the action of the group of auxiliary devices. For this purpose the copying paper in the shape of the so-called endless type customary in copying machines 45 undergoes a special treatment providing it with markings or perforations at predeter-

mined distances apart. These markings or perforations are utilized for acting upon sensitive parts of the machine, which parts, by releasing catches, transmit or shift power 50 to the auxiliary devices at the moment they are to enter into action.

By the use of this prepared copying paper all multiple and intermediate gearing for working the auxiliary devices is fixed and proportionate intervals is done away with 55 and the machine requires no adjustment by hand, its action being entirely automatic.

The invention is shown in perspective in the annexed drawing.

The copying paper 1 has perforations 2, spaced so as to coincide with the length of the originals for copying which the machine 60 is to be used.

Of the copying machine only the shaft 3 65 is shown, on which is mounted a feeler or trailer 4 which normally glides loosely on the copying paper. The paper is suitably supported and the feeler 4 engages in a perforation or cavity 2, when unsupported, 70 owing to its weight. This slight movement of the feeler acts in co-operation with other parts of the machine in shifting or switching power to the auxiliary devices and causing them to enter into action at the proper 75 moment.

I claim:

A device for automatically actuating the feeding and cutting mechanism of copying machines of the endless band type including 80 a rock shaft which extends transversely of the endless band, said shaft being arranged for connection to the feeding mechanism, and a relatively wide gravity tongue on said shaft, said tongue being adapted to drop in 85 slots located at intervals in the endless band.

In testimony whereof, I have hereunto set my hand in presence of two witnesses.

RICHARD BERGER.
